US00D895444S

(12) **United States Design Patent** (10) Patent No.: **US D895,444 S**
DeBoer et al. (45) Date of Patent: ** Sep. 8, 2020

(54) **DISPLAY DEVICE**

(71) Applicant: **Johnson Controls Technology Company**, Auburn Hills, MI (US)

(72) Inventors: **Dave P. DeBoer**, Cedarburg, WI (US); **Tai P. Luc**, South Milwaukee, WI (US); **Kirk P. Henderson**, Oconomowoc, WI (US); **Tushar Baviskar**, Milwaukee, WI (US); **Ramesh Varma Shiva Satya Bhupathiraju**, Telangana (IN); **Vinod Tijare**, Milwaukee, WI (US); **Krishna Danturti**, Milwaukee, WI (US); **Satish Kumar Jatashanker Singh**, Pune (IN); **Swapnil Subhash Chavan**, Milwaukee, WI (US)

(73) Assignee: **Johnson Controls Technology Company**, Auburn Hills, MI (US)

(**) Term: **15 Years**

(21) Appl. No.: **29/634,248**

(22) Filed: **Jan. 19, 2018**

(51) LOC (12) Cl. **10-04**

CLAIM

We claim the ornamental design for a display device, as shown and described.

DESCRIPTION

FIG. 1 is a front top perspective view of the display device; FIG. 2 is a rear top perspective view of the claimed design of FIG. 1;

FIG. 3 is a front view of the claimed design of FIG. 1; FIG. 4 is a rear view of the claimed design of FIG. 1; FIG. 5 is a left side view of the claimed design of FIG. 1; FIG. 6 is a right side view of the claimed design of FIG. 1; FIG. 7 is a top view of the claimed design of FIG. 1; and, FIG. 8 is a bottom view of the claimed design of FIG. 1. Any portion of the article depicted in broken lines forms no part of the claimed design.
